UNITED STATES PATENT OFFICE.

WARREN SMITH, OF HAWKINSVILLE, GEORGIA, ASSIGNOR OF ONE-HALF
TO CHARLES T. KING, OF DE LEON SPRINGS, FLORIDA.

COTTON-SEED DROPPER.

SPECIFICATION forming part of Letters Patent No. 630,752, dated August 8, 1899.

Application filed February 10, 1899. Serial No. 705,191. (No model.)

To all whom it may concern:

Be it known that I, WARREN SMITH, residing at Hawkinsville, in the county of Pulaski and State of Georgia, have invented certain 5 new and useful Improvements in Cotton-Seed Droppers, of which the following is a specification.

My invention is an improvement in cotton-seed droppers, and has for an object to provide 10 a simple economical construction which will efficiently serve the desired purpose; and the invention consists in certain novel constructions and combinations of parts, as will be hereinafter described, and pointed out in the 15 claim.

In the drawings, Figure 1 is a side view of 20 a cotton-seed dropper constructed according to my invention. Fig. 2 is a top plan view of same, and Fig. 3 is a vertical longitudinal section of the machine.

The machine has a framing comprising the two side beams A A. These beams A are lapped at their front ends on opposite sides of the draft-bar B, to which they are secured 25 by the bolts C, such bolts serving to rigidly connect the front ends of the beams as well as to secure said beams to the draft connection B. This draft connection B has the horizontal arm B', which is lapped between the 30 front ends of the beams A and the upright arm B' at the front end of the arm B', which upright arm is suitably adapted for the attachment of the draft devices, it may be, by providing said arm with perforations b² to receive the draft-hook of a whiffletree or in other suitable manner as may be desired.

In the arm B' of the draft connection B, I provide an opening D' for the upright portion of the track-clearer D, such upright portion 40 having a notch or opening d' to receive the bolt C, which intersects the opening D', so such bolt will operate to lock the track-clearer in position.

The beams A are provided in rear of the 45 clearer D with bearings for the opener-wheel E, such bearings being preferably provided in blocks E', secured to the under side of the beams A, as shown in Figs. 1 and 3. This wheel E not only operates to form a cut in the 50 ground to receive the cotton-seed, but it also gives motion to the seed-dropping drum. To

this end its axle E' is provided with a sprocket-wheel E², receiving the sprocket-chain F, which also passes around a sprocket-wheel G' on the seed-dropping drum G, as shown in Fig. 1. The drum G has pockets g, and is suitably journaled in bearings a on the beams A, and operates between cross-beams H H, which extend between the beams A, one in advance and the other in rear of the drum G.

The seedbox I is supported on the cross-bars H and the side beams A and fits over the drum G, having in its bottom a concaved plate K, provided centrally with an opening k, with which register the pockets g in the drum G as the latter is turned in the operation of the machine. This concave plate properly directs the seed to the pockets g and prevents any waste during the operation of planting.

At one end the drum G is provided with a sprocket-wheel, which is geared by a sprocket-chain L with a sprocket-wheel L' on one end of a stirrer-shaft M. This shaft M is journaled to the seedbox and is provided within the same with stirrer-arms m, which tend to agitate the seeds and prevent the same from becoming too lumpy to properly discharge as the dropping-drum is revolved.

The coverer-blade N extends from side to side below the rear part of the seedbox and in rear of the seed-dropping drum and is connected by the spring-blades N' with the blocks E³. These blades extend on opposite sides of the pockets g of the seed-dropping drum G, and therefore do not interfere with the seed-dropping operation. The spring-blades, together with the coverer, form an elastic springy support for the rear end of the seed-dropping device, and thus render the operation of same easier, as will be readily understood.

Having thus described my invention, what I claim, and desire to secure by Letters Patent, is—

An improvement in cotton-seed droppers 95 consisting in the combination of the seedbox having the concave plate K provided with the opening k, the beams spaced apart and supporting the seedbox at their rear ends, the opening-wheel, the boxes for said wheel secured to the opposite beams, the seed-dropping drum journaled below the plate K and

having its rim moving close to the walls of the opening *k* and provided with pockets *g* movable into register with the opening *k*, gearing between the opening-wheel and the dropping-drum, the stirring-shaft operating in the seedbox above the plate *K* and having pins *m*, gearing between said shaft and the opening-wheel, the coverer arranged in rear of the dropping-drum and having its plate *N'* extended forward on opposite sides of the pockets *g* and secured at their forward ends to

the boxes of the opening-wheels and the draft-bar having arms *B* and *B'* and opening *D'*, the track-clearer *D* notched at *d'* and the cross-bolt *C* all substantially as and for the purpose set 15 forth.

WARREN ^{his} X SMITH.
